UNITED STATES PATENT OFFICE.

WILLIAM P. WITHEROW, OF PITTSBURGH, PENNSYLVANIA, ASSIGNOR TO WITHEROW STEEL COMPANY, OF PITTSBURGH, PENNSYLVANIA, A CORPORATION OF PENNSYLVANIA.

CAR STEP AND METHOD OF MAKING THE SAME.

Application filed December 26, 1922. Serial No. 608,946.

To all whom it may concern:

Be it known that I, WILLIAM P. WITHEROW, a citizen of the United States, residing at Pittsburgh, in the county of Allegheny and State of Pennsylvania, have invented 5 a new and useful Improvement in Car Steps and Methods of Making the Same, of which the following is a full, clear, and exact description.

10 The present invention relates to car steps such as used with freight cars for assisting the brakeman in boarding and alighting from the cars.

Heretofore such steps have customarily 15 been formed from flat bars of substantially uniform shape and cross-section throughout. With such steps, there has been provided a comparatively poor tread surface and in wet and slippery weather serious accidents have 20 often resulted. By the present invention, there is produced, preferably by die-rolling, an improved blank from which a safety car step may be inexpensively formed and which overcomes the objections to car steps as 25 ordinarily used.

In the accompanying drawings, I have shown for purposes of illustration only certain preferred embodiments of my invention, it being apparent that many changes 30 in construction may be made without departing from the spirit of my invention and scope of my broader claims.

In the drawings—

Figure 1 is a side elevation of a die-roll 35 blank from which a car step is adapted to be formed;

Figure 2 is a top plan view of the construction illustrated in Figure 1;

Figures 3, 4 and 5 are transverse sectional views respectively, on the lines III—III, 40 IV—IV and V—V of Figure 2;

Figure 6 is a side elevation, partly broken away, of a completed car step formed from the blank illustrated in Figures 1 and 2, and

45 Figure 7 is a side view of a slightly modified form of car step.

In carrying out the present invention, I preferably utilize a billet or leader having a cross-sectional area which is substantially 50 equal to the maximum cross-sectional area of the completed article to be formed therefrom. This leader is then die-rolled in any suitable manner to produce a blank having flattened terminal portions 2 and an inter-

mediate flattened tread forming portion 3. 55 The tread forming portion 3 is preferably provided during the die-rolling operation with a roughened tread forming surface which may be produced by rolling therein a series of corrugations or ridges 4. Intermediate the terminal portions 2 and the tread forming portion 3 the blank preferably has cylindrical hanger portions 5. The respective portions of the blank preferably 60 gradually merge, one into the other, by forming inclined connecting portions 6, whereby abrupt changes of section and stress magnification factors are eliminated.

By a suitable bending operation, the die-rolled blanks may be bent into the form 70 illustrated in Figure 6. Either before or after this final bending operation, the terminal portions 2 may be drilled to provide openings 7 permitting the step to be secured 75 in place beneath the body of a car.

In some instances, it is desirable to form 80 steps for attachment to the sides of cars, a step for this purpose being illustrated in Figure 7. This step may be produced by twisting the terminal portions 2 through substantially 90° or by initially rolling the terminal portions at right angles to the position illustrated in Figures 1 and 2.

It will be understood that the blanks may 85 be produced in connected series by die-rolling as is common in this art and then separated into individual blanks as shown in Figure 1, in any desired manner.

By the present invention, there is provided 90 a car step having an efficient tread surface tending to prevent the foot of the brakeman from slipping.

Further advantages arise from the provision of a die-rolled step having an efficient 95 distribution of the metal therein to insure maximum strength.

I claim:

1. As an article of manufacture, a die-rolled safety car step of different cross sectional shapes at different portions throughout the length but free from abrupt changes of section, said step having attaching terminal portions and an intermediate roughened tread forming portion, substantially as described. 100

2. As an article of manufacture, a die-rolled safety car step having flattened terminal portions, a flattened intermediate tread 105

forming portion and circular hanger portions intermediate the terminal portions and tread forming portions, substantially as described.

3. As an article of manufacture, a die-rolled safety car step having flattened terminal portions, a flattened intermediate tread forming portion and circular hanger portions intermediate the terminal portions and tread forming portions, said step being free from abrupt changes in section, substantially as described.

4. As an article of manufacture, a die-rolled safety car step having flattened terminal portions, a flattened intermediate tread

forming portion and circular hanger portions intermediate the terminal portions and tread forming portions, said tread forming portion having a roughened tread surface, substantially as described.

5. As an article of manufacture, a safety car step having a broad roughened tread forming portion, supporting portions, and portions of gradually changing cross section connecting said portions, substantially as described.

In testimony whereof I have hereunto set my hand.

WILLIAM P. WITHEROW.
